DOOR LOCK

Ernest L. Schlage, Burlingame, Calif., assignor to
Schlage Lock Company, a corporation

Application August 10, 1948, Serial No. 43,471

4 Claims. (Cl. 292—244)

1

This invention relates to a door lock, and especially to a reversible dead latching mechanism therefor.

The object of the present invention is generally to improve and simplify the construction and operation of dead latching mechanisms, and especially to provide a latching mechanism including a main latch bolt and a cooperating dead latch both of which are reversible as a unit to permit either right or left hand installation of the lock and latching mechanism as a whole in doors.

The invention is shown by way of illustration in the accompanying drawings in which:

Fig. 1 is a perspective view of the reversible latch bolt unit;

Fig. 2 is a perspective view of the latch bolt actuating unit;

Fig. 3 is a perspective view of the retractor bar;

Fig. 4 is a perspective view of the retractor bar hinge block;

Fig. 5 is a vertical longitudinal section showing the lock mounted in a door and with the door in closed position, said view showing the main latch bolt engaged with the striker plate on the door jamb, and the dog on the inner end of the retractor bar ready to engage the shoulder on the anchor plate;

Fig. 6 is a sectional view similar to Fig. 5, but taken at right angles thereto, said view showing the dead locking bolt depressed by the striker plate;

Fig. 7 is a sectional view similar to Fig. 5, but with the door in open position and the main latch bolt extended;

Fig. 8 is a sectional view similar to Fig. 7, but taken at right angles thereto and showing both bolts extended.

Fig. 9 is a perspective view of the main latch bolt;

Fig. 10 is a perspective view of a retainer plate which is applied to the main latch bolt;

Fig. 11 is a perspective view of the main latch bolt pin;

Fig. 12 is a vertical cross-section taken on lines XII—XII of Fig. 5, and in the direction of the arrows;

Fig. 13 is a vertical cross-section taken on lines XIII—XIII of Fig. 5, and in the direction of the arrows;

Fig. 14 is a vertical cross-section taken on lines XIV—XIV of Fig. 5, and in the direction of the arrows;

Fig. 15 is a perspective view of a sleeve which cooperates with the dead locking bolt, and

Fig. 16 is a perspective view of the same sleeve,

2

but looking at the end opposite that shown in Fig. 15.

In the customary installation, a door latch actuating unit A is inserted in a hole 2 drilled transversely of a door C, and a latch bolt unit B is inserted in a hole 3 drilled at right angles to the hole 2 through the edge of the door and interengages the unit B. A key 5, see Figure 12, is inserted in the unit A from the exterior of the door and actuates a flat spindle bar 4, which in turn actuates the latch bolt mechanism. The spindle bar may also be rotated by a knob 6 or turnpiece disposed on the inside of the door. The unit A is provided with a pair of anchor posts 7 and an escutcheon plate 9. Screws 8 pass through a thumb piece escutcheon 10, see Figure 8, and secure the unit A in the transverse hole 2 of the door. The unit B includes a face plate 11 secured to the edge of the door by screws 12.

Extending from the face plate 11 is cylindrical latch bolt housing 14 from the rear end of which projects a double anchor plate 15. This double plate has central openings formed therein in which is journaled a crank arm 16 actuated by the spindle bar 4 which extends through a slot-like opening 4a therein. The anchor plate 15 is also provided with a pair of openings 17, see Figure 1, one at each end to receive the anchor posts 7 of the unit A.

When assembling the lock in a door the unit B is first inserted in the hole 3, and when so inserted, the anchor plate 15 projects into the transverse hole 2. The unit A is then inserted in the hole 2 and as it is inserted, the posts 7 pass through the openings 17 in the anchor plate and the spindle bar 4 passes through the opening 4a in the crank arm 16. The escutcheon plate 10, which carries the turnpiece 6, is then applied and the screws 8 are inserted and tightened. Finally screws 12 are fastened and both units are secured in place and are interlocked with each other.

Included in the unit B is a main latch bolt 20 indirectly coupled to the inner end of which is a retractor bar 21, see Figures 3, 5, and 6. The retractor bar 21 projects through the inner end 14a of the housing 14, see Figure 1. It is channel shaped in cross-section to provide a pair of depending side walls contoured to form a pair of cams 22. The crank arm 16 carries a pin 16a at its outer end and this extends through an enlarged opening 16b formed in the inner end of the retractor bar 4 in the direction of arrow a, see Figure 5. The pin 16a engages the retractor bar and retracts it together with the main latch bolt 20 indirectly connected to the outer end thereof.

When the spindle bar 4 is released, the latch bolt and the retractor bar assume a normal or projected position as they are at all times acted upon by a spring 23.

Formed on the inner end of the channeled retractor bar 21 are dogs 25 positioned under certain conditions to engage shoulders 26 formed on the double anchor plate 15, and when such engagement is made, the main latch bolt 20 is dead locked. The dogs are actuated into and out of the path of the shoulders 26 by the cams 22 and by a cup 27, see Figures 5, 6, 15 and 16, slidably mounted within the latch bolt housing. The cup 27 is in turn actuated by a dead locking bolt 20a which is preferably a round bar or pin having one flat side 20b to contact a flat face 20c of the main latch bolt 20. The inner end of the dead locking bolt 20a has a grooved head 20d formed thereon and this extends into an arcuate slot 28 formed in the closed end of the cup 27. The slot extends slightly more than 180 degrees and has a cut away portion 28a to permit introduction of the grooved head 20d. The closed end of the cup 27, see Figures 15 and 16, is provided with a central opening 29 and has a rectangular notch 30 to provide a guide for the retractor arm. An adjacent portion 31 of the cup 27 is cut away and a portion 32 is flattened to engage the cams 22 of the retractor bar.

Suitably secured in the central opening 29 of the cup 27 is a hub 33 which supports and guides a spring 24. This spring normally maintains the cup 27 and the dead locking bolt 20a in a projected position as shown in Figures 7 and 8. In this position the flattened portion 32 of the cup engages the cams 22 of the retractor bar and elevates the inner end of the bar to a position where the dogs 25 ride above the shoulders 26, thus leaving the main bolt 20 and the dead locking bolt 20a free to be depressed for example when the door is being closed. When the door is fully closed as shown in Figures 5 and 6, the main latch bolt 20 assumes a projected position and the dead locking bolt 20a assumes a depressed position against the strike plate 50. The flattened portion 32 on the cup assumes a position out of engagement with the cams 22 and the dogs 25 drop into a position to engage the shoulders 26, thus preventing a depression of the main latch bolt or dead locking the same.

The retractor bar 21 is pivotally secured to a loose block 39 by a pin 34 in order to provide a fulcrum to permit elevation or lowering of the dog 25 with relation to the shoulder 26. The pivoted end of the retractor bar is shaped to form a forked bell-crank 35, see Figures 3 and 5, so that it will straddle a pin 36. This pin is carried coaxially by the main latch bolt 20 and is retained against removal therefrom by a plate 37 which is secured by staking or flanging in a sleeve-like extension 38 formed at the rear end of the main latch bolt. The pin 36 has two collars 36a and 36b formed thereon to limit the end-wise movement of the pin with relation to the main latch bolt to an amount just sufficient to permit free swinging movement of the bell-crank 35. The collar 36b engages the bell-crank and is held in such engagement by the spring 23. The pin 36 serves two main functions, first, that of a guide and retainer for the spring 23 and second, that of directing the spring pressure to the bell-crank, so that the dogs 25 on the inner end of the retractor bar are urged in a downward or engaged position with relation to the shoulders 26. The spring 23 similarly serves two main

functions, first, that of urging the cup 27 outwardly normally to maintain the dead locking bolt in extended position and second, that of urging the cams 22 to elevate the dogs 25.

To accomplish reversability of the main and cooperating dead locking bolts as a unit to permit either right or left hand installation of the lock in doors, the outer face plate 11 is backed by an inner plate 11a, the plates being secured together by riveted portions 11b. The latch bolt housing 14 is provided at its outer end with an annular flange extending between the outer and inner plates 11 and 11a to form a swivel permitting the face plate 11 and the inner plate 11a to be rotated about the outer end of the latch bolt housing. As the face plate 11 has a non-circular opening therein fitting the contour of the main latch bolt 20 and the dead locking bolt 20a, these bolts must rotate with the face plate 11 and the inner plate 11a when they are rotated about the axis of the latch bolt housing.

As the retractor bar is held against rotation with relation to the latch bolt housing 14 because it engages the crank arm 16 the main latch bolt 20 rotates with relation to the retractor bar. In all positions of rotation a floating pivotal support is provided by the hinge block 39, see Figures 3, 4 and 5. This block has a hole 34a to receive the pivot pin 34 and has upper and lower flat edges 40 and 41 formed thereon. The lower flat edge 41 rests on the pin 36 and the upper flat edge loosely engages the inner surface of the sleeve-like extension 38 formed on the latch bolt. The block 39 is accordingly held between the sleeve 38 and the pin 36 no matter how the sleeve 38 of the main latch bolt 20 is rotated about it.

A rotating connection is also formed between the dead locking bolt and the cup 27, the cup 27 being held against rotation by the portion thereof that straddles and forms a guide for the retractor bar. As shown in Figures 12, 15 and 16, the rectangular shaped notch 30 formed in the end of the sleeve 27 provides a pair of guide shoulders 30a engaging the opposite sides of the retractor bar. The grooved head 20d of the dead locking bolt extends into the arcuate slot 28 and interlocks therewith. The extent of the slot 28 is such that it is possible to rotate the dead locking bolt through 180 degrees with relation to the cup 27. A rotation of half is all that is necessary as only a half turn of the main and the dead locking bolts is required to change them from right hand to left hand position, or vice versa.

The cup 27 is actuated by the spring 24 and the dead locking bolt 20a. The spring 24 is guided throughout its movement by a hub 33 on the cup and by a hub 33a secured to a disc pressed against the inner end of the latch bolt housing. The dead locking bolt when depressed moves the cup 27 against the spring 24 to assume an innermost position as shown in Figure 5. The dead locking bolt is depressed or moved inwardly in unison with the main latch bolt 20 by abutment of the sleeve 38 with the cup 27 when the latch bolt engages and cams over a striker plate 50 as shown in Figures 5 and 6, for instance when closing the door. The dead locking bolt is held depressed by the striker plate 50 as long as the door is closed since there is no opening in the striker plate for the dead locking bolt to extend into. Therefore, while both bolts are depressed when the main bolt is in engagement with the striker plate 50, only the main latch bolt 20 can again project through a striker plate opening 51 having the

cross-sectional shape of the latch bolt. The dead locking bolt on the other hand stays depressed and retains the cup 27 in that position thereby leaving the dogs 25 in dogging position under the urgency of the spring 23 so as to maintain the main latch bolt 20 dead locked when the door is closed. When the door is opened either by the key mechanism 5 or the turnpiece 6, the rotary movement of the spindle bar 4 imparts a swing movement to the crank arm 16 in the direction of the arrow *a*, see Figure 5, causing the crank pin 17a to engage the inner end of the retractor bar through the enlarged opening 16b and raise the dogs 25 free of the shoulders 26. Further rotation of the crank arm 16 retracts the main latch bolt 20 from the striker plate 50 thus permitting opening of the door. When the key mechanism 5 or the turn piece 6 is released, springs 23 and 24 restore all parts to normal position and project both the main latch bolt and the dead locking bolt.

While the latch bolt housing 14, the retractor bar 21 and the cup 27 are non-rotatable, both of the bolts 20 and 20a and the face plate 11 and the inner plate 11a are rotatable with relation to these members. By providing for such relative rotation, the same lock structure may be applied to either right hand or left hand doors.

Having thus described my invention, what I claim and desire to secure by Letters Patent is—

1. In a lock structure, a housing having a circular portion, a face plate mounted on said portion and adapted to be swung relative to said housing about an axis to positions 180 degrees apart, said face plate being provided with a non-circular aperture, a bolt mounted in said housing for oscillation to positions 180 degrees apart and axially reciprocable with respect to said housing, a portion of the cross section of said bolt being formed complementarily to a portion of said aperture to prevent swinging said bolt relative to said face plate, a retractor bar mounted in said housing for axial movement relative to said housing, means constraining said retractor bar against rotation relative to said housing about said axis, a block hingedly connected to said retractor bar at one end of the latter and slidably engaging said bolt to permit oscillation of the latter relative to said bar.

2. In a lock structure, a bolt adapted to be reciprocated along an axis, said bolt being provided with a recess opening axially outwardly thereof, an elongated axially extending pin projecting from said bolt through said recess, a collar on said pin spaced from said bolt, an elongated retractor bar extending substantially parallel to said axis for so reciprocating said bolt and having one end disposed in said recess, a forked bell crank on said one end straddling said pin at a point between said bolt and said collar and in engagement with said collar, a block slidably engaging the side wall of said recess and hingedly secured to said one end of said bar to permit oscillation of said bolt about said axis relative to said bar and to permit tilting of said bar relative to said block to different angles of inclination relative to said axis.

3. In a locking structure, an elongated housing having a cylindrical end, a face plate apertured to receive a latch bolt and a dead locking bolt therethrough, said aperture being non-circular and complementarily formed relative to

the combined cross sections of said bolts, said face plate being swingably received on said cylindrical end for swinging with said bolts about the axis of said housing to positions 180 degrees apart relative to said axis for securement to left or right hand doors, means on said face plate for securing the same to a door in one of said positions, said bolts being reciprocably supported in said housing in either one of said positions, an elongated retractor bar for moving said bolt and extending generally parallel to said axis and tiltable relative to said axis between dogging and undogging positions, a block slidably engaging said latch bolt and hingedly secured to one end of said bar to permit said swinging of said bolt relative to said axis and to permit said tilting of the bar relative to said axis, a cup slidably supported in said housing and engageable with said bar for tilting the same to undogging position, spring means urging said bar to dogging position at all times, said cup being provided with an arcuate slot concentric with said axis, said dead locking bolt being provided with a reduced portion loosely received in said slot to permit swinging said dead locking bolt between said positions when said cup is stationary.

4. In a lock structure, an elongated housing having a cylindrical end, a face plate apertured to receive a latch bolt and a dead locking bolt therethrough, said aperture being non-circular and complementarily formed relative to the combined cross sections of said bolts, said face plate being swingably received on said cylindrical end for swinging with said bolts about the axis of said housing to positions 180 degrees apart relative to said axis for securement to left or right hand doors, means on said face plate for securing the same to a door in one of said positions, said bolts being reciprocably supported in said housing in either one of said positions, an elongated retractor bar for moving said bolt and extending generally parallel to said axis and tiltable relative to said axis between dogging and undogging positions, a block slidably engaging said latch bolt and hingedly secured to one end of said bar to permit said swinging of said bolt relative to said axis and to permit said tilting of the bar relative to said axis, a cup slidably supported in said housing and engageable with said bar for tilting the same to undogging position, spring means urging said bar to dogging position at all times, said cup being provided with an arcuate slot concentric with said axis, said dead locking bolt being provided with a reduced portion loosely received in said slot to permit swinging said dead locking bolt between said positions when said cup is stationary, said cup being provided with an axially extending groove for receiving said retractor bar therein to prevent relative rotation between said cup and said bar.
